BUILDING CONSTRUCTION

Harold Earl Raymond, New Orleans, La.

Application January 8, 1936, Serial No. 58,146

1 Claim. (Cl. 108—1)

My present invention relates to improvements in the construction of buildings, especially adapted for use where severe weather stresses are experienced, or where it is desirable to provide a roof of comparatively small exposed area to these stresses.

This invention is specifically intended to provide an extremely light and most scientific construction which should be readily and economically erected.

This invention further is intended to provide a means of construction, in which there is an arch roof of curvature based on scientific contour, which arch may be of sufficient length to cover a wide floor area without the necessity of intermediate supports.

This invention is more particularly intended to provide a light construction, having the arches, the axis of which, are formed on one or more parabolic curves designed to take the direct thrust of the load as well as any moment of eccentricity.

This invention is intended to cover a construction of parabolic arch construction of flange members proportioned according to their eccentricity from the line of force, maintaining the same cross sectional area, with shear taken care of by diagonal members of tubular or structural shapes.

This invention is especially intended to provide an arch structure which may be restrained at its springing by either wall or buttress resistance or fixed columns restraint.

This invention will be more fully understood by reference to the accompanying drawing, in which like parts indicated by similar reference numerals throughout the several views and in which

Figure 1 is a front elevational view of the improved construction with parts of the overhead bracing broken away.

Figure 2 is an end view seen from the left of Figure 1.

Figure 3 is an enlarged detailed view of the footing shown in Figure 1.

Figure 4 is an enlarged view in side elevation of the parts shown in Figure 3.

Figure 5 is a top plan view of the parts shown in Figure 4, and taken along the line 5—5.

Figure 6 is an enlarged detail view of one of the plates shown in Figure 2.

Figure 7 is an enlarged end view as seen from the left of the parts shown in Figure 6, and

Figure 8 is a perspective view of the improved

footing with parts of the arch structure broken away.

Referring more particularly to the drawing the numeral A designates a concrete footing poured in the usual way to provide a resisting force of the direct thrust as well as to support the live and dead load to be carried. As shown in the various figures of the drawing, the column is made continuous by embedment in a pocket in the footings.

The arches F as particularly shown in Figure 1 are formed of continuous members of equal sectional areas (or segments welded together where practical construction requires). The end portions of these arches are restrained by the columns C anchored as above described.

In order to provide the necessary strength for various loadings with equal flanges of a parabolic arch design the effective depth of the arches is increased accordingly as the stresses increase and vice versa. In the type of construction where contour lines are required by architectural features, false work B may be provided to conform to these requirements.

While primarily the object of this invention is to use welded connections, for practical purposes of erection or shipping, it may be desired to use riveted, bolted or welded (electric, oxy-acetylene or thermite) connections D to join pre-fabricated members.

The invention further embraces the use of clip angles E for purlins which are similar to those used for fish plates in railroad construction, but of a design to effect continuity of the purlins with bolted or riveted construction.

As shown in Figure 5 the footing is of T shape and the column C is partly embedded in the head portion of the footing with its greater part embedded in the shank portion of the footing. This particular construction and mounting of the column gives the desired resistance to vertical and horizontal thrust in opposite directions and supports the arch and roof against vertical load as against horizontal wind load.

From the fundamental nature of an arch, the dead load it carries tends to produce a deflection downward in the center of the span and an outward thrust at the base of the columns and footings. The present invention resists this thrust of the footing by providing a wide and flat area of bearing in the footing to act against the vertical surface of the adjacent soil. This area is proportioned to the amount of horizontal thrust of the arch, as the thrust of the arch originates at the springing of the arch (top of column) and is

resisted at the ground level, its tendency to overturn the column is resisted by the bearing of the footing on both sides below grade, and the embedding of the column in the pocket of the footing makes both act as one.

In building construction it is necessary to contend with the horizontal wind pressure on the roof. Mechanics show that this causes an outward thrust on one side of the building and an inward thrust on the opposite side. The footing of the present invention acts equally well in both directions as well as against turning (moment), as the bearing against the soil is the same on both sides and the column is embedded in a pocket in the footing.

It is obvious that various changes and modifications may be made in the details of construction and design of the above specifically described embodiment of this invention without departing from the spirit thereof, such changes and modifications being restricted only by the scope of the following claim.

I claim:

In building construction, an arch support, comprising a footing of concrete or the like substantially T shape in horizontal cross section 5 adapted to be embedded in the ground with its head portion transverse to the axis of the arch and with its shank portion extending inwardly along the axis of the arch, said head portion providing flat wings with opposite flat surfaces for resisting outward and inward thrust transmitted through the arch, and a vertical column 10 adapted for positioning beneath the side of the arch at substantially the point of springing of the arch and having its lower end embedded in the footing throughout substantially the depth of the footing and with the column disposed coaxially of the arch and shank portion of the footing and partly in the head portion thereof.
